UNITED STATES PATENT OFFICE.

EDWARD C. COLLINS, OF TAUNTON, MASSACHUSETTS.

CAR-BRAKE-OPERATING DEVICE.

SPECIFICATION forming part of Letters Patent No. 641,638, dated January 16, 1900.

Application filed August 3, 1899. Serial No. 726,000. (No model.)

To all whom it may concern:

Be it known that I, EDWARD C. COLLINS, of Taunton, in the county of Bristol and State of Massachusetts, have invented certain new 5 and useful Improvements in Car-Brake-Operating Devices, of which the following, taken in connection with the accompanying drawings, is a specification.

My invention relates to brake-operating 10 devices for cars; and it consists in certain novel features of construction, arrangement, and combination of parts which will be readily understood by reference to the description of the accompanying drawings and to the claims 15 hereto appended and in which my invention is clearly pointed out.

Figure 1 of the drawings is an elevation of my improved handle. Fig. 2 is a central vertical section of the same. Fig. 3 is a trans- 20 verse section on line xx in Figs. 1 and 2. Fig. 4 is an elevation of the upper portion of the brake-shaft. Fig. 5 is a perspective view of one of the ratchet-engaging pawls. Figs. 6 and 7 are respectively a central vertical sec- 25 tion and a transverse section of a handle in which the ratchet-teeth are formed in a steel bushing.

In the drawings, 1 represents the brake- handle, provided with the large hollow hub 2, 30 in the interior of which is formed a series of ratchet-teeth 3, preferably an odd number, extending longitudinally of said hub or parallel to the axis about which said handle moves in operating the brake.

The upper end of the brake-shaft 4 is en- 35 larged, has formed therein the circumferential groove 5, has its extreme upper portion 6 reduced in diameter to form the two shoul- ders 7 and 8, has a transverse cylindrical open- 40 ing 10 formed therein central between the shoulders 8 and 9, and has a central longitudi- dinal slot 11 extending from the shoulder 9 to its upper end, as shown in Fig. 4. The re- duced upper portion 6 has fitted thereon ring 45 12, which abuts against the shoulders 7 and 8 and has its upper end slightly countersunk, and the upper end of the portion 6 of the brake-shaft is expanded into said coun- 50 tersink to firmly secure said ring in position thereon. The exterior of the upper portion of the ring 12 is fitted to a bearing in the upper end of the chamber in the hub 2 of the

handle, and the portion of said brake-shaft immediately above and below the groove 5 is fitted to a bearing in the lower portion of the 55 chamber in said hub, as shown.

A coiled spring 13 is placed in the circular opening 10, and the two pawl-plates 14, each provided on its inner edge with the rectangular notch 15 to receive an end of said spring, 60 are placed in the slot 11, one on each side of the spring 13, the tension of which tends to force both of said pawls outward into contact with the teeth 3 when placed in position within the chamber of the hub 2, as shown 65 in Figs. 3 and 7.

As the slot 11 is cut diametrically through the center of the upper portion of the brake- shaft 4 and two pawls 14 are placed therein and project therefrom on opposite sides there- 70 of, and as there is an odd number of teeth 3 within the hub 2, it follows that when one pawl is engaging with the shoulder of one tooth the opposite pawl is bearing against the central portion of a tooth 3 upon the opposite 75 side of the chamber of the hub 2, as shown in Figs. 3 and 7, and said pawls may act alter- nately upon the teeth 3, whereby a much stronger tooth may be had, with an equally fine adjustment of the handle, as if a single 80 pawl and double the number of teeth were employed.

The handle 1 is secured against being ac- cidentally withdrawn from the brake-shaft by the screw 16, the smooth inner end of which 85 enters the groove 5, as shown in Figs. 2 and 6.

In some cases I propose to form a cylin- drical chamber in the hub 2 and fit therein a steel bushing 17, in which are formed the se- 90 ries of teeth 3, as shown in Figs. 6 and 7, said bushing being provided upon its exterior with a lug 18, which fits into a groove in the in- 95 terior of the chamber of the hub 2, as shown. This construction makes a very strong, dura- ble, and effective brake-operating device, and that will not easily get out of order.

What I claim as new, and desire to secure by Letters Patent of the United States, is—

1. In a car-brake-operating device the com- bination of a brake-shaft having a longitudi- 100 nal slot cut diametrically through its upper end; a binding-ring embracing the extreme end of the slotted portion of said shaft, to tie

the two prongs thereof together; a brake-handle provided with a chambered hub to embrace the upper end of said shaft and revolve thereon; a series of ratchet-teeth formed 5 in the wall of said chamber; a pair of radially movable pawls fitted to said slot from opposite sides of said shaft and having a combined width, at their ends, substantially equal to the diameter of said shaft; and a spring 10 interposed between said pawls and operating to move both of said pawls outward or away from each other to cause them to be alternately engaged by said ratchet-teeth.

2. In a car-brake-operating device the combination of a brake-shaft having a longitudinal slot cut through its upper end; a binding-ring embracing the extreme end of the slotted 15 portion of said shaft to tie the two prongs thereof together; a pair of pawls fitted to said

slot from opposite sides of said shaft; a spring 20 interposed between said pawls and acting to force them outward or away from each other; a brake-handle having a chambered hub fitted to and inclosing the upper end of said shaft, and said pawls; a series of ratchet-teeth formed in the wall of said chamber, and 25 extending longitudinally thereof and adapted to engage said pawls; and means for preventing movement of said handle endwise of said shaft.

In testimony whereof I have signed my name to this specification, in the presence of two subscribing witnesses, on this 1st day of August, A. D. 1899.

EDWARD C. COLLINS.
